UNITED STATES PATENT OFFICE.

JOHN G. MACPHERSON, OF PHILADELPHIA, PENNSYLVANIA, ASSIGNOR TO
THE MACPHERSON AUTOMOBILE COMPANY, OF NEW JERSEY.

VAPORIZER FOR GASOLENE-ENGINES.

SPECIFICATION forming part of Letters Patent No. 655,407, dated August 7, 1900.

Application filed November 22, 1899. Serial No. 737,865. (No model.)

To all whom it may concern:

Be it known that I, JOHN G. MACPHERSON, a citizen of the United States, residing at Philadelphia, in the county of Philadelphia 5 and State of Pennsylvania, have invented certain new and useful Improvements in Vaporizers for Gasolene-Engines, of which the following is a specification.

My invention relates to improvements in vaporizers for gasolene-engines; and the main object of my invention is to provide an accurate and a certain means for supplying the necessary amount of the gasoline and for quickly vaporizing the same.

Another object of my invention is the provision of a means for supplying the gasoline which is operated and is so adjustable as to only allow the desired amount of gasoline to be supplied and which is entirely cut off 20 when the engine is out of operation.

Another object of my invention is the provision of a means for heating the gasoline by employing an exhaust-flame at every explosion of the engine, so as to entirely vaporize 25 the gasoline applied thereto.

Another object of my invention is the provision of a vaporizer which can be attached to any gasolene-engine and which is very simple, durable, and inexpensive in construction 30 and is the embodiment of a very practical and useful mechanism.

To attain the desired objects, the invention consists of a vaporizer for gasolene-engines embodying novel features of construction 35 and combination of parts substantially as disclosed herein.

In the drawings, Figure 1 represents a side elevation of the invention with one end of the cylinders broken away; and Fig. 2 is a 40 vertical section taken through the cylinders and the casing of the gasolene-supply valve with the operating means connected to a suction-valve, which is simply shown to illustrate the operation of my vaporizer.

Referring to the drawings, A designates the 45 large glass receptacle or cylinder, having located therein the small heating-cylinder B. Leading from the outside into the heating-cylinder is the flame-conducting pipe C, hav-

ing the valve D therein. Passing through 50 one end of the small cylinder and out into the air is the escape-pipe E. An opening F is made in the upper side of the large cylinder and in it screws tightly the threaded sleeve or tube G, which is made more secure 55 therein from breakage by means of a threaded lug or boss H. Formed in the lower end is a conical channel or opening J, which leads upward to the larger straight opening or channel K, which terminates in a smaller 60 straight channel L, which leads to the gasolene-supply pipe M, which is secured in the enlarged threaded end N of the tube.

Fitting in the channels of the tube is the 65 rod O, carrying the needle point or valve P upon its lower end, said point being adapted to project beyond the lower end of the tube. Surrounding the rod and having one end secured thereto and the other end abutting against the rim Q of the tube is a coiled or 70 spiral spring R to normally hold the needle-valve in engagement in the lower end of the tube.

Pivoted or fulcrumed in the lug S is the 75 bell - crank lever T, whose inner end S' is adapted to be below the needle-valve and is provided with an inclined guard or plate T' to cause the gasoline to run off of the lever and drop upon the small cylinder. Attached to the outer or lower end U of the lever is a 80 rod V, which is connected to a gas-inlet or suction-valve W, said valve being adapted to pull upon the lever, whose inner end moves upward, contacting the lower end of the needle-valve and opening the tube, thus 85 causing the gasoline to flow therefrom and down upon the heating-cylinder, where it is vaporized and passes out of the gas-supply pipe X to the engine. Thus it will be observed that when the engine is thrown out of 90 operation the supply of gasoline is stopped, and thereby all danger is avoided.

It is evident that I provide a vaporizer 95 which is very simple in its construction and by reason of its few parts is not easy to put out of operation by breakage, which is provided with a supply-valve that is made adjustable by simply turning a milled ring or

nut Y, which allows the tube to be raised or lowered, and which is thoroughly efficient and very practical when in use.

I claim:

- 5 In combination with a gasolene or gas engine, of a vaporizer, consisting of a cylinder within a cylinder, a flame-jet entering the inner cylinder, a spring-actuated gasolene-admitting valve located above the inner cylinder in the top of the outer cylinder, a lever fulcrumed upon the exterior of the outer cylinder and having a free end within and

one without the cylinder, a guard or plate carried by the lever near the free inner end thereof to prevent gasolene from flowing too far upon the lever, and means for operating the lever to cause its inner end to contact the valve to admit gasolene to be vaporized.

In testimony whereof I affix my signature in presence of two witnesses.

JOHN G. MACPHERSON.
